Fig. 4

Fig. 6

Fig. 5

FIGURE 1 is a top plan view of a compartmented tray embodying my new design;

FIGURE 2 is a side elevational view of the tray of FIGURE 1;

FIGURE 3 is an end view of the tray viewed from the right end of FIGURES 1 and 2;

FIGURE 4 is a fragmentary side elevational view viewed from the right of FIGURE 3 showing the central portion of the side wall;

FIGURE 5 is a fragmentary vertical sectional view taken on the line 5-5 of FIGURE 1; and

FIGURE 6 is a perspective view of the tray of FIGURES 1 to 5.

I claim:

The ornamental design for a compartmented tray, as shown.
